Inventor,

Harry Cheshire
by Horace Pettit,
his Attorney.

UNITED STATES PATENT OFFICE.

HARRY CHESHER, OF PHILADELPHIA, PENNSYLVANIA.

THUMB-LATCH FOR DOORS.

SPECIFICATION forming part of Letters Patent No. 692,827, dated February 11, 1902.

Application filed June 12, 1901. Serial No. 64,263. (No model.)

To all whom it may concern:

Be it known that I, HARRY CHESHER, a citizen of the United States, and a resident of the city of Philadelphia, State of Pennsylvania, have invented certain new and useful Improvements in Thumb-Latches for Doors, of which the following is a full, clear, and exact description, reference being had to the accompanying drawings, forming part of this specification.

My invention relates to certain improvements in door-latches; and the principal object of the said invention is to provide means for preventing the latch-lever or its handle from being removed from the door from the outside by unscrupulous persons.

With this end in view the invention consists in providing a latch-lever having a groove or grooves provided on its side intermediate its length, the said grooves being adapted to engage a slotted keeper which is secured on the interior face of the door, thereby preventing the said latch-lever from being withdrawn through the slot in the door after the handle on the outside of the door is unscrewed or removed therefrom.

My invention further consists in the combination and arrangement of the parts, such as hereinafter fully set forth, and particularly pointed out in the claims made hereto.

Referring to the accompanying drawings, Figure 1 is a sectional elevation illustrating a portion of the door having my invention applied thereto. Fig. 2 is a perspective view of a portion of the interior face of a door, illustrating the projecting inner end of the latch-lever, also the keeper, the latch-bar being omitted.

In the said drawings, 1 designates a door or gate, which is provided with a slotted opening 2, adapted to receive the latch-lever 3. The outside of the door is provided with a grip or handle 4, of the usual construction, having flanges 5, which are secured to the door by means of the usual screws 6. The upper flange of the handle is provided with a rectangular slot or opening 7, which is in line with the transverse slot 2 in the door and through which the latch-lever 3 passes, as clearly shown in Fig. 1 of the drawings.

The latch-lever 3 is of the usual construction found in devices of this character, hav-

ing a thumb-piece 8 on its outer end and a shoulder 9 on its lower side adjacent to the thumb-piece, which abuts against the lower edge of the slot 7 provided in the flange of the handle. The upper portion of the latch-lever at a point adjoining the thumb-piece is provided with a curved projection 10, which passes through the slot 7 and operates to prevent the latch-lever from being withdrawn through the said slot 7 except when the lever is tilted upwardly at such an angle as to allow the shoulder 9 to pass through the slot 7. This lever 3 cannot be tilted sufficiently to withdraw it from the slot 7 so long as the handle 4 is secured in its position on the interior of the door.

In order to prevent the latch-lever 3 from being withdrawn through the slot 2 in the door in the event of the handle 4 being unscrewed, I provide the sides of the said lever with the grooves 11, a number of said grooves being provided, so as to accommodate doors of different thicknesses. A keeper 12 is provided, having a slot 13 extending from its upper edge to a point about central of the said keeper, the said slot fitting in the grooves 11, as illustrated in Fig. 2. The grooves 11 are of a sufficient width to allow the latch-lever 3 to be tilted for the purpose of lifting the bolt 14.

It will thus be seen that in my construction it will be impossible to withdraw the latch-lever from the outside of the door even if the handle 4 were unscrewed and removed from the door, as the shoulders formed by the grooves 11 would abut against the flat face of the keeper 12 and prevent its withdrawal. The handle 4 would also be protected, because it could not be removed from the latch-lever by reason of the thumb-piece 8, which is much wider than the width of the slot 7, and therefore could not be withdrawn without the latch-lever being withdrawn with it.

I am aware that the latch construction is an old and well-known device, and only desire to claim the features as herein set forth for retaining the latch-lever in its position, and thus preventing the removal of the latch-lever and its handle by unscrupulous persons.

Having thus described my invention, what I claim, and desire to secure by Letters Patent, is—

1. In a door-latch, the combination of a latch-lever adapted to pass through a slot in the door, a slotted keeper on the outside of the door which forms a bearing for the thumb-latch, grooves formed in the latch-lever adjacent the inner face of the door, and a keeper adapted to engage the said grooves, for the purpose described.
2. In a door-latch, the combination of a latch-lever adapted to pass through a slot in the door, a handle secured to the outside of the door having a slotted extension through

which the latch-lever passes, grooves formed on the sides of the latch-lever adjacent the interior face of the door, and a keeper secured to the door having a slotted opening, the vertical walls of which engage the grooves of the latch-lever, substantially as described. 15

In witness whereof I have hereunto set my hand this 11th day of June, A. D. 1901.

HARRY CHESHER.

Witnesses:

CHARLES H. SPECKMAN,
